UNITED STATES PATENT OFFICE.

WILLIAM J. SMITH, OF PHILADELPHIA, PENNSYLVANIA, ASSIGNOR OF ONE-HALF TO
WILLIAM R. BLAIR, OF PHILADELPHIA, PENNSYLVANIA.

OIL-WELL PUMP.

Application filed April 6, 1925. Serial No. 20,899.

To all whom it may concern:

Be it known that I, WILLIAM J. SMITH, a citizen of the United States, residing at Philadelphia, in the county of Philadelphia and State of Pennsylvania, have invented certain new and useful Improvements in Oil-Well Pumps, of which the following is a specification.

This invention relates to pumps, and it relates particularly to pumps intended for use in oil and other wells in which a permanent casing for the wells is employed.

The object of the invention is to provide a pump having operating means combined therewith intended for use in cased wells, which, by reason of its construction and relative arrangement of parts, shall be capable of being lowered into a well and operated for an indefinite time without requiring adjustment or repair, to raise fluid from the bottom of a well. A further object of the invention is to provide, in a pump of the kind referred to, in simple form, a motor and fluid forcing means connected therewith adapted to be lowered into a cased well, a connection between the motor and a pump or other fluid-forcing means located at the top of a well for supplying the motor with an operating fluid, and means whereby the fluid in the well shall be forced upward in the casing and discharged from the top thereof.

While the pump is hereinafter described, in connection with a cased oil well, and is particularly intended for raising oil in a well of this form, it is not intended in this way to limit the scope of the invention, as the construction involved is adapted for use in many other similar positions.

A simple form of embodiment of the invention is illustrated in the accompanying drawing, in which:

Figure 1 is a central vertical sectional view of the pump, a portion of the casing of a well in which the pump is located in use being also shown in section.

Figure 2 is a horizontal sectional view on the line 2-2 of Figure 1.

Figure 3 is a horizontal sectional view on the line 3-3 of Figure 1.

Figure 4 is a horizontal sectional view on the line 4-4 of Figure 1.

Figure 5 is a horizontal sectional view on the line 5-5 of Figure 1.

In this drawing 1 represents the casing of

a well, which is of the usual cylindrical form, of equal diameter throughout, and is preferably provided at its lower end, intended to be located at or near the bottom of a well from which the contents are to be withdrawn, with perforations 2 for admitting, in conjunction with the open lower end of the casing, the contents of the well into the casing.

In the form of pump herein shown all the working parts are contained in a cylindrical body 3, which in diameter is somewhat less than that of the casing 1. This outer face of the body 3 is provided with a number of projecting longitudinal ribs 4 to serve as guides and for preventing canting and wedging of the cylinder in lowering or raising the pump in the casing 1, and for positioning the cylinder when in the casing in such relation to the casing as to maintain a uniform circular space between the two. One of the ribs 5 is formed with a passage 6 extending through it, such passage forming part of one of the conduits by which a fluid is introduced into and withdrawn from the pump in the operation of the latter.

Arranged in the upper end of the cylinder 3 is a screw head 7 having an opening receiving the end of a pipe or tube 8 through which operating fluid is received, and provided with an eye bolt 9 for the attachment of a rope or the like used in lowering the pump into a well or raising it therefrom.

The interior of the cylinder has in it a partition 10, which divides the cylinder to form the motor chamber 11 and the suction chamber 12. The partition has in it a screw threaded central opening which receives the hollow screw threaded stem 13 of a circular valve seat 14, the stem being held in place in the partition by a binding nut 15. The valve seat is spaced from the lower face of the partition forming a chamber 16 which is connected by openings 17 with the space between the pump and the casing 1 when the pump is in position for use in the casing.

Arranged in the chamber 16 is a disk valve 18 having a central opening receiving the stem 13 of the valve seat, and by which it is guided in its up and down movements in the operation of the pump. The valve seat 14 has in it a series of openings 19 through which communication is established between the suction chamber 12 and the chamber 16, such openings being automatically alter-

nately exposed and closed by the disk valve in the operation of the pump.

A second partition 20 forming the lower end of the suction chamber 12 is secured within the cylinder 3 near the lower end thereof. Extending through the partition 20 are a series of openings 21 through which communication between the lower open end of the cylinder and the suction chamber 12 is afforded. A disk valve 22 is arranged above the partition 20 and is held in operative position by a headed screw 23 passing through the valve and entering the partition.

15 In order that the lower portion of the space between the pump and the casing of the well, when the pump is in position for use, and the upper portion of such space, may be separated, and thus, while oil may 20 be drawn from the lower portion, the upper may serve as a conduit for the oil to be raised, the pump is so constructed as to shut off communication between those parts of the space. This may be accomplished in 25 many ways, preferably by providing the exterior of the pump with a flexible projection which surrounds the pump and fills the space between the pump and the well casing, and a simple means for the purpose is 30 shown in the drawings. This consists of a leather cup packing 24 of an exterior diameter corresponding to the interior diameter of the casing 1, and located between the inlet and outlet openings of the suction chamber 35 of the pump. The lower flange portion 25 of the packing is secured between a circumferential rib 26 extending from the outer face of the cylinder and a screw ring 27 engaging screw threads on the outer face 40 of the cylinder. This attaching means allows the ready securing of the packing and permits of the quick removal and replacement of worn or injured packing.

45 The pump is operated by a fluid under pressure alternately introduced and withdrawn from the top of the motor chamber 11 through the pipe or tube 8, and correspondingly introduced and withdrawn from the bottom of the chamber through a pipe 50 or tube 28, the passage 6 and the port 29 connecting the passage and the lower part of the motor chamber. The fluid may be introduced and withdrawn by any suitable means, as by a pump, not shown, at the top 55 of the well.

Located in the chamber 11 is a piston 30 having connected therewith a piston rod 31 which extends through the hollow stem 13 of the valve seat 14. In the stem and surrounding the rod is a gland packing 32 by which passage of fluid under pressure from one of the chambers 11 and 12 to the other is prevented. Connected to the piston rod 31, and located in the suction chamber 12, is 65 a piston 33. This piston has openings 34

extending through it, and has on its upper face a disk valve 35 provided with a central opening receiving the piston rod 31. Obviously, the valve will be seated on the piston to close the openings in the latter, by the 70 pressure of a fluid, on the upward movement of the piston, and will be raised from its seat to expose the openings on the downward movement of the piston.

In the use of the pump, assuming it to 75 have been lowered into the casing of a well to a position where the fluid to be raised enters the lower portion of the casing of the pump, a fluid is alternately introduced into the motor chamber, through the described conduits, above and below the piston 30, causing the latter to reciprocate. This reciprocating movement being transmitted to the piston 33, the latter in its upward movement acts as a sucker to draw in 80 to the chamber 12, through the openings in the partition 20, and the openings 2 in the cylinder 1, the liquid contained in the well, the valve 22 being in this movement raised to expose the openings through the 85 partition. The piston 33 in its upward movement acts as a ram to force a liquid previously drawn into the chamber 12, raising the valve 18, and thus establishing a 90 communication through the chamber 16 and the ports 17 to the space between the pump and the casing of the well, and thence into the casing above the pump, by which the liquid is conducted to discharge at the top 95 of the well. On the downward movement 100 of the piston 33 the valve 35 is opened and the valve 22 in the lower partition is closed. Consequently, the fluid drawn into the chamber 12 in the upward movement of the piston passes through the openings 34 in 105 the piston 33, and on the ensuing upward movement of the piston it is trapped and forced through the course described, ultimately to the top of the well. By reason of 110 the packing or dam established in the space between the pump and the casing of the well, no interference between the suction and forcing operations of the pump is possible, as the cup packing will be expanded by 115 the imposition of the weight of the column of the fluid being raised in the casing, and the greater the weight so imposed, the greater expansion and consequent effectiveness of the packing for its designed purpose.

120 I claim:

1. A pump of the kind described comprising a cylindrical shell or casing provided with elongated exterior ribs extending longitudinally of the shell or casing, a piston located in the shell or casing, means for reciprocating the piston, a second piston connected and movable with the first, and located in a chamber having inlet and outlet openings, the exterior of the shell 125 130

or casing being provided with a surrounding flexible projection located between the inlet and outlet openings of the chamber.

2. A well casing, a pump of the kind described comprising a shell or casing less in diameter than the casing of the well adapted to be lowered into the casing, septate chambers in the shell or casing of the pump, a piston arranged in one chamber, means for alternately admitting a fluid under pressure to the opposite sides of the piston for reciprocating it, and a valved piston connected to the first, and located in a second chamber having inlet openings and communicating with the space between the pump and the casing.

3. A well casing, a pump of the kind described comprising a shell or casing of less diameter than the casing of the well, adapted to be lowered into the casing, septate chambers in the shell or casing of the pump, a piston arranged in one chamber, means for admitting a fluid under pressure

to the opposite sides of the piston alternately, for reciprocating it, and a valved piston connected to the first and located in a second chamber having inlet openings and communicating with the space between the shell or casing of the pump and the well casing, the shell or casing of the pump being provided with an exterior packing adapted to dam the space between the pump and the well casing.

4. A pump of the kind described comprising a cylindrical shell or casing provided with elongated exterior ribs extending longitudinally of the shell or casing.

5. A pump of the kind described comprising a cylindrical shell or casing provided with elongated external ribs extending longitudinally of the shell or casing, one of such ribs having a passage therethrough.

In testimony whereof I affix my signature.

WILLIAM J. SMITH.
